TIME SETTING ATTACHMENT FOR
RADIOS

John H. Campbell, Fyffe, Ala.

Application April 5, 1939, Serial No. 266,208

3 Claims. (Cl. 200—39)

This invention relates to an improved time setting device for radios adapted to be actuated automatically for turning on the radio at a predetermined time.

More particularly, it is an aim of this invention to provide an automatic switch for radios adapted to be actuated by an electric alarm clock to close a circuit from a source of current to a radio at a predetermined time.

Still a further aim of the invention is to provide an automatic time control switch for radios adapted to be actuated by an electric clock for closing a circuit to the radio at a predetermined time and for maintaining the circuit in a closed position.

This invention may be associated with a radio as a separate switch for completing a circuit to a radio at a predetermined time when the conventional switch thereof is in an open position for automatically energizing the radio, and the attachment is preferably provided with a manually controlled switch whereby it may be disconnected when its use is not desired and under such circumstances the radio may be manually controlled through its conventional switch. However, if preferred the circuit associated with the automatic time controlled attachment may be substituted for conventional circuit and switch of the radio.

While the invention has been illustrated and will be described as an attachment for completing a circuit to a radio, it is to be understood that it is equally well adapted to other uses where an electric switch may be automatically controlled such as for controlling lighting or electrical burglar alarm systems, for example.

Other objects and advantages of the invention will hereinafter become more fully apparent from the following description of the drawings, which illustrate a preferred embodiment thereof, and wherein:

Figure 1 is a front elevational view of a radio equipped with the time setting attachment.

Figure 2 is a top plan view of the time setting mechanism which includes a conventional electric alarm clock works.

Figure 3 is a side elevational view showing the clock works associated with the automatic switch controlling means, said means being positioned so that the switch is in a closed position.

Figure 4 is an enlarged side elevational view partly in section illustrating the construction of the contact members forming the switch and showing their relative position to the switch controlling mechanism.

Figure 5 is an edge view in elevation showing the circuit making and breaking mechanism, as they would appear when the contacts are in their open position.

Figure 6 is a horizontal sectional view taken along the line 6—6 of Figure 4 showing the circuit controlling mechanism in the same position, as seen in Figure 5.

Figure 7 is a horizontal sectional view taken along the line 7—7 of Figure 4 and showing the construction of the two cog wheels which complete the circuit through the switch.

Figure 8 is a fragmentary elevational view, partly in section, showing the parts as seen in Figures 6 and 7 in engagement, a portion of the movable contact member being shown in its projected position as it would appear with the switch closed, and

Figure 9 is a diagrammatic view showing the electric circuit to the clock and the circuit through the automatic switch to the radio leading from the clock circuit, intermediate of its ends.

Referring more particularly to the drawings, wherein like reference characters designate like or corresponding parts throughout the different views, 10 designates generally a radio of conventional construction in the front panel of which is mounted an electric alarm clock 11, which likewise may be of any suitable construction.

The motor 12 of the clock 11 is adapted to be connected to a suitable electrical outlet, not shown, by the plug 13 which is connected by the wires 14 and 15 to the motor 12 to complete a circuit therethrough.

The clock works, designated generally 16, and as best seen in Figure 2 is conventional and only those parts thereof which are connected with the automatic switch controlling mechanism will be described.

A shaft 17 is journaled in the brackets 18 secured to the clock 11 and has one end projecting outwardly through the front panel of the radio 10 and provided with a knob 19 for rotating the shaft and the gear wheel 20 carried thereby.

A shaft 21 is secured at one side of the clock works 16 and is connected at one end to the back plate 22 of the clock works and at its opposite end to a sleeve 23 secured to the front plate 24 of the clock, as best seen in Figures 5 and 7. A gear 25 is rotatably mounted on the reduced inner end of the sleeve 23 and is enmeshed with the gear wheel 20, while a gear wheel 26 is slidably and rotatably mounted on shaft 21 behind the gear

25 and is provided with an integrally formed sleeve 27 projecting toward the back end of the clock 11, for a purpose which will hereinafter be described.

5 As seen in Figure 7, gear 25 is provided with a pressed out portion to form a slot or recess 28 while the gear 26 is struck up to form the projection 29 to engage slot 28 when the two gears are positioned in a certain point of their movement 10 relatively to each other as will hereinafter be explained. Projection 29 has a rounded or cam shaped portion 30, as seen in Figure 5 for releasing it from recess 28 when gear 25 is turned in one direction relatively thereto.

15 Referring now to Figures 2 and 3, gear 25 is enmeshed with gear 31, which forms a part of the clock works 16 and which is connected to the alarm setting hand 32 so that by turning knob 19 gear wheel 20 will actuate gear 25 to turn gear 20 31 and hand 32 and as the gears 25 and 31 are of the same size they will turn at the same speed. Gear 26 is enmeshed with the relatively wide gear wheel or cog 33 which connects with and drives the hour hand 34 and as gears 26 and 33 are likewise of the same size they will also turn at the same speed and it will thus be seen that gear 26 25 is constantly moving when the clock 11 is running and will complete a revolution every 12 hours.

25 A stationary contact element 35 is secured to plate 24. A pair of spaced brackets 36 are secured to and project forwardly from plate 22 to mount the pin or rod 37. A movable contact 38 has the angularly disposed lugs or ears 39 which are loosely mounted on rod 37 between the brackets 36 to mount contact element 38 for a swinging movement relatively to element 35. A coil spring 40 carried by pin 37 and having one terminal engaging element 38 cooperates with the contractile coil spring 41, attached to said element and adjacent its upper end, to normally urge it forwardly and into engagement with contact 35.

35 Contact 38 is provided with the portion 42 which is disposed adjacent to shaft 21 and which 45 engages the sleeve 27 to normally hold contact 38 in its retracted position, as seen in Figure 2, out of engagement with contact 35.

The radio 10 is connected to the heretofore mentioned electrical outlet through the circuit 50 which includes the wire 43 which extends from the radio and connects with the wire 15, the wire 44 which extends from the radio to the stationary contact 35 and the wire 45, which is provided with the make and break switch 46 which connects wire 14 to the movable contact 38, so that when switch 46 is closed and contacts 35 and 38 are in engagement, a circuit will be completed through wires 43, 44 and 45, and through wires 14 and 15 to the plug 13 which is connected to 55 an electrical outlet to energize the radio 10.

60 From the foregoing it will be seen that as heretofore described knob 19 may be turned to turn gears 20, 25 and 31 to set the alarm hand 32. Assuming that the manually operated switch 65 46 is in its closed position, and that the plug 13 is connected with a source of electrical current so that the wires 14 and 15 complete a circuit through the electric clock 11, the hour hand 34 will be revolved by the clock mechanism 16 driven by the motor 12 and with it will turn the cog or gear 33 to revolve gear 26. As the hour hand 34 and gear 33 will be turning in a clockwise direction, as seen in Figure 3, the gear 26 will be turned in a counter-clockwise direction so that 70 the cam shaped end 30 of the projection 29 will

be the leading end of the projection. When the hour hand 34 reaches the time at which the alarm hand 32 is set, at which time it will be disposed directly in a line therewith, the projection 29 will have moved to a point where it is in alignment with the recess 28 so that it will move into engagement with this recess when projected by contact 38 which is urged outwardly by springs 40 and 41 to thereby allow contact 38 to move into engagement with contact 35 to complete a circuit through wire 45, the two contacts, wire 44 and wire 43 to energize the radio 10. It is to be assumed, of course, that the radio 10 has been previously set for the program desired so that this station will be tuned in when the radio is energized by the circuit making mechanism. Springs 40 and 41 are of sufficient strength to retain the gear 26 in a projected position to retain projection 29 in recess 28, to cause gears 25 and 26 to rotate together until such time as it is desired to turn off or deenergize the radio. This is accomplished manually by opening switch 46. To again set the time control mechanism, knob 19 is turned in a counter-clockwise direction to thereby turn gear 25 in a clockwise direction so that the tapered end of the recess 28 will ride over the cam surface 30 to retract gear 26 and thereby move contact 38 away from contact 35 so that switch 46 can be closed without energizing the radio 10. Knob 19 is turned counter-clockwise until the alarm hand is again set at the desired time so that when this time is reached the circuit will again be closed, to the radio 10, as heretofore described.

35 Various modifications and changes in the construction and arrangement of the parts forming the invention are contemplated and may obviously be resorted to and the right is therefore expressly reserved to make such variations and changes as fall within the spirit and scope of the invention as hereinafter defined by the appended claims.

I claim as my invention:

1. A device of the class described comprising a stationary contact, a vertically pivoted contact having spring means for normally projecting it into engagement with said stationary contact,

means rotated by the hour hand shaft of a clock for normally retaining said pivoted contact in a retracted position out of engagement with the stationary contact, means connected with the alarm setting hand shaft of said clock for releasing said first mentioned means when the hour hand and alarm hand of said shafts are aligned to release the pivoted contact, and a manually controlled shaft for adjusting the last mentioned means relatively to said first mentioned means and for retracting the first mentioned means and the pivotally mounted contact.

2. A time controlled switch comprising a gear provided with a recess, said gear being connected to a gear of a clock works and which is connected to the alarm setting hand of the clock, a slidably mounted gear provided with a projection for engagement with said recess, said last mentioned gear being enmeshed with a gear of the clock works connected to the hour hand, said gears being of the same size whereby each will make a complete revolution with a revolution of said hands, a pair of contacts forming a part of an electric circuit, one of said contacts being pivotally mounted and in engagement with the gear provided with the projection, said projection normally holding the gear, of which it forms a part in a retracted position by engagement

with the gear provided with the recess, spring means for projecting said movable contact and the gear which it engages when said projection and recess are aligned for moving the projection into engagement with the recess so that said contacts may be closed, and manually actuated means for rotating the first mentioned gear to reset the alarm hand and to retract the pivotally mounted contact.

- 5 10 3. A time controlled electric switch including a fixed contact and a pivotally mounted contact, a spring for normally urging the pivoted contact into engagement with the fixed contact; a shaft provided with a turning knob, a gear keyed to 15 the shaft, a fixed shaft, a gear rotatably mounted thereon and in mesh with a gear keyed to an alarm setting shaft, of a clock, provided with a setting hand, said last mentioned gear having an elongated inclined recess, a second gear rotatably and slidably mounted on said fixed shaft and in mesh with a cog keyed to the shaft of the

hour hand of the clock, said slidable gear being provided with a lug, projecting from one side thereof, said lug having an inclined end and being shaped to fit said recess, said lug normally engaging a side of the recessed gear and being held thereby in a retracted position and being in engagement with the pivoted contact to hold it in a retracted or open position, said lug and recess being aligned, when the hour hand and alarm hand are aligned, so that the spring can project the lug into engagement with the recess thereby moving its gear to a projected position to permit the pivoted contact to be moved by the spring to a closed position, and said turning knob being operable to rotate the recessed gear 15 to reset the alarm hand and to move the recess out of engagement with the lug, to retract the sliding gear and the pivoted contact to reopen the switch.

JOHN H. CAMPBELL. 20
